UNITED STATES PATENT OFFICE.

BENJAMIN F. MAYO, OF SALEM, MASSACHUSETTS, ASSIGNOR TO UNITED SHOE MACHINERY CORPORATION, OF PATERSON, NEW JERSEY, A CORPORATION OF NEW JERSEY.

HEELING-MACHINE.

1,377,263.

Specification of Letters Patent. Patented May 10, 1921.

Application filed August 5, 1918. Serial No. 248,334.

To all whom it may concern:

Be it known that I, BENJAMIN F. MAYO, a citizen of the United States, residing at Salem, in the county of Essex and State of Massachusetts, have invented certain Improvements in Heeling-Machines, of which the following description, in connection with the accompanying drawings, is a specification, like reference characters on the drawings indicating like parts in the several figures.

This invention relates to such machines as those employed for attaching heels to shoes. More particularly does it concern means for supplying the heels or heel parts, as the top lifts, and carrying them to the attaching positions. It also is directed to carrying or transferring means for the nails employed in securing the heels and top lifts to the shoes.

An object of the invention is to increase the automatic effect of machines of the character above-mentioned, enabling them, without undue complication or interference with the control of the machine, to perform operations for which a helper is usually employed.

As a feature of the invention, there is provided means operating incidentally to different acts performed upon the work, to control a device for bringing different work portions into coöperation with each piece of work. This control may be exercised by the main work support, as the jack post engaging the lasted shoes, and by operating mechanism, as that which acts upon the work in the nailing operation. When a plurality of kinds of work portions, as heels and top lifts, are to be presented to the work, I preferably convey them by holding devices which are movable in one direction from their normal positions. To accomplish this, I have shown power means to which the holders are temporarily connected by a clutch through movement of the work-support. Preferably, the power means acts oppositely under the influence of the work-support, so that the holders are not only brought into coöperation with the work but are also returned to normal. A frictional connection between the power means and holders may permit the first work portion to be presented to the work without disconnection of the power, the first holder being temporarily retained in co-

operation with the work while the friction slips. This arrangement also provides for the stopping of the holders at the extremes of travel.

Another feature of the invention has to do with the supply of work parts, there being heel and top lift containers situated together at the same side of the work-engaging means, as the nail block or jack post, with means for conveying the contents of the containers to the engaging means. This arrangement enables such an organization as the frictionally connected power means previously mentioned, to effect the successive delivery of the work portions through movement in one direction. I prefer to control the delivery from the containers by means mounted thereon, and an effective way to actuate at least one delivery means is by the holder which it supplies. To this end, I have shown a portion of the lift top delivering means in the path of the holders, while, to avoid actuation in incorrect timing, the companion delivering means is clear of the holders.

A further feature of the invention is found in the control of the nail-transferring mechanism by the conveying mechanism for the heel parts. In the illustrated embodiment of the invention, the transferring mechanism or loader is moved from its nail-receiving to its nail-delivering position by the conveying mechanism or swing plate and is returned by a spring. In the delivery position it is preferably retained during the discharge of the nails by engagement with the conveying mechanism. This, both for the movement and retention of the transferring mechanism, may be through the co-operation of a projection and a wall or flange relatively movable over one another. Operative engagement between these parts may be effected by the yieldability of one and released by an opening in the wall through which the projection passes upon movement in one direction only.

Other features will hereinafter appear and, together with those already outlined, are illustrated in the accompanying drawings, in which—

Figure 1 is a side elevation of a portion of a heel-attaching machine illustrating one form of my invention;

Fig. 2 is an enlarged horizontal section on the line 2—2 of Fig. 1;

Fig. 3 is a partial broken front elevation, looking from the right of Fig. 1;

Fig. 4 is a vertical sectional detail through the pivotal axis of the swing plate 5 on the line 4—4 of Fig. 2;

Fig. 5 is a horizontal sectional detail on the line 5—5 of Fig. 3;

Fig. 6 is a broken perspective view of the heel container; with a portion of the swing 10 plate; and

Fig. 7 is a similar view of the top lift container.

The numeral 10 designates the frame of a heel-attaching machine of the character disclosed in Patent No. 1,157,688 to Glidden, dated October 26, 1915. Operating at the top of the machine is a work-spindle 12, carrying at its lower extremity a cap 14 at the under side of which is mounted an adjusting slide 16 for a jack post 18. In the lower portion of the frame operates a cross-head 20, in which is mounted a nail block 22 having openings to receive drivers carried by a driver plate 24 situated at the upper end of a spindle 26. Movable above the nail block is the conveying or holding mechanism for parts to be applied to the work, these parts in the present instance consisting of heels and top lifts. This conveying mechanism is furnished by a swing plate 28 mounted upon a spindle 30 journaled in vertical bearings at the rear of the cross-head and in an arm 31 depending from the under side of said cross-head. To the top of the spindle is secured a flanged collar 32 having at its upper side a friction washer 34 of some such material as leather. The end of the spindle passes through the collar and is reduced and threaded at 36 to receive an elongated nut, a cylindrical portion 38 of which extends through the opening by which the swing plate is pivoted. Between a head 40 at the top of the nut and the swing plate is a helical compression spring 42 acting to force the plate against the washer 34 and compel its movement with the spindle 30 when this is rotated, though allowing the plate to slip on the spindle when a stop member is interposed in the path of the plate or elements carried therewith. Normally free to turn upon the spindle between the cross-head and the bearing in the arm 31 are upper and lower bevel gears 44 and 46, respectively. These gears are constantly driven in opposite directions, as indicated by the arrows in Fig. 3 of the drawings, by a bevel pinion 48 meshing with them and fastened upon a shaft 50 turning in bearings in the cross-head. At the outer extremity of the shaft 50 is a worm wheel 52 having in mesh with it a worm 54 fixed upon a shaft 56 journaled in the cross-head and connected to a suitable source of power. Either gear 44 or 46 may be joined to the spindle 30 by a clutch, here shown as

of the jaw type and having a member 58 splined on the spindle. The clutch member and the adjacent faces of the pinions have circular series of projections and depressions adapted to secure the member 58 with either of the pinions for rotation. The member 58 is provided with an annular groove, into which extends the points of projections 60 from opposite sides of the yoke-shaped end of a lever 62 fulcrumed at 64 upon the cross-head. Pivoted at 66 to the lever 62 is a bell-crank lever 68 fulcrumed at 70 on the frame 10. An upwardly extending arm 72 of the lever 68 is curved forwardly toward the work spindle 12, and has contacting with it the edge of a cam arm 74 upon a lever 76 fulcrumed at 78 on the cap 14 of the work-spindle. The opposite arm of the lever 76 contacts with a projection 80 from the jack post 18, the relation being such that, as the jack post is moved inwardly, the lever 76 shifts the bell-crank lever 68 to raise the clutch member 58 into engagement with the upper gear 44, thus turning the spindle 30 and swing plate in an anti-clockwise direction as viewed from above. A spring 81 maintains contact between the levers 68 and 76 and projection 80, so that, upon opposite movement of the jack post, the bell-crank lever 76 is swung inwardly to shift the clutch member 58 into engagement with the lower bevel gear and reverse the movement of the spindle and swing plate.

Carried upon the upper surface of the swing plate are heel and top lift holders having breast gages 82 and 84, respectively, adjustably clamped in position by screws 86 and 88 passing through slots in the side arms of the gages. The heads of the screws are located in depressions extending along the slots, so that the tops of the screws are substantially flush with the upper surfaces of the gages. Fork members 90 and 92 of the holders co-operate with the breast gages, their shanks moving in ways 94 and being retained in place by screws 96 passing through slots in the shanks. The forks are automatically moved toward and from the breast gages in the oscillation of the swing plate. For this purpose, a bell-crank lever 98 is fulcrumed at 100 on the swing plate and has a rounded end entering between lugs 102, 102 projecting from one side of the shank of fork 92. Carried by the cross-head at the left-hand edge of the swing plate is a pin 104, in the direction of which the lever 98 is normally urged by a spring 106, this also tending to move the fork toward the breast gage. At the inner side of the shank of the fork 92 is an arm 108 contacting with an arm 110 upon the shank of the fork 90. These arms are held in contact and the fork 90 toward the breast gage by a spring 112. When the swing plate is at its initial or ex-

treme position at the left and the lever 98 in contact with the pin 104, this lever and the arms 108 and 110 separate the forks from the breast gages against the tension of the 5 springs, so that heels and top lifts may be readily inserted in their respective holders. Then, when the lever and projection pass out of contact, the springs draw the forks toward the breast gages to clamp the heels and 10 top lifts in the holders for presentation to the work and nailing mechanism.

Situated side by side at the left of the nail block, alined with the heel and top lift holders when these are in their initial position, are heel and top lift containers or 15 magazines 114, 116, respectively. These containers are in the form of tubes, of a cross-section corresponding to the parts they are to contain, and are supported by arms 118, 20 118 fixed to the frame 10. Mounted on the container 114 are supporting means, shown as comprising spindles 120, 120 rotatable in bearings secured to the container wall. At the inner end of each spindle is a lever 122, 25 the lower end of which is curved at 124 beneath the end of the container tube, giving a horizontal supporting surface for the bottom heel of the stack. The upper extremity of each lever at 126 is provided with a vertical yieldable engaging surface which may 30 be furnished by a spring 127 extending into an opening in the side of the container tube for contact with the second heel of the stack. The relation between the ends 124 and 126 35 is such that, when the former is beneath the container supporting the heels therein, the end 126 is withdrawn from its opening, leaving the heel opposite and those above free to move downwardly, but, as the lower end of 40 the lever is swung to one side and just before the bottom heel drops, the succeeding heel is engaged by the springs 127, supporting the stack until the levers are moved in the opposite directions. Fixed to the forward ends of the spindles 120 are arms 128 45 and 130 joined to one another by a slot and pin connection 132. The arm 130 is a portion of a bell-crank lever, the other arm 134 of which extends downwardly and lies in the 50 path of a projection 136 rising from the upper surface of the swing plate. In the clockwise movement of the swing plate, the projection 136 strikes the arm 134 just as the heel holder is positioned beneath the container 114. The resulting movement of the 55 arm 134 is imparted to the arms 130 and 128, swinging the levers 122 to deliver the lower heel of the stack in the manner already described. Opposite travel of the projection 60 136 by its contact with the other side of the arm 134 restores the levers 122 to their normal positions.

At the bottom of the container 116 is a bracket 138 supporting a horizontal slotted 65 guide arm 140. In this guideway moves a

top lift supporting slide 142, which is drawn normally beneath the container by a spring 144, thus supporting the stack of top lifts. The clockwise movement of the swing plate carries the top lift breast gage 84 beneath the 70 heel container without interference with its elements, which are out of the line of travel, but when the top lift container is reached, the securing arm of the gage strikes the forward end of the slide 142, forcing it back in 75 the guideway, as is best seen in Fig. 7, and permitting the lower top lift to drop into its holder upon the swing plate. Upon reverse movement the arm of the breast gage supports the succeeding top lift until the 80 slide can be drawn by its spring beneath it to sustain the remainder of the stack. It should be observed that in this delivery position for both the heels and top lifts, the forks are drawn back by the mechanism already described, so the work portions may be 85 freely introduced to the holders.

The clockwise or restoring movement of the swing plate is unimpeded between its extreme positions, these being indicated in 90 full and dotted lines at the left and right, respectively, of Fig. 2. In the opposite or heel and top lift conveying movement of the swing plate, a latch 146 pivoted upon an arm 148 fixed to the lower extremity of the 95 spindle 30 and normally raised by a spring 150 seated in a chamber depending from the arm, comes in contact with a stop projection 152 from the arm 31. This causes the movement of the swing plate under the influence of the spindle to stop when the heel holder is alined with the nail block, the frictional connection between the plate and spindle slipping to permit this. When the operator brings the nailing mechanism into 100 action to drive the nails through the heel, a contact arm 154 on the nail plate or its supporting parts strikes the tail of the latch 146, freeing it from engagement with the projection. This permits the driving mechanism to rotate further the swing plate until 105 the top lift holder arrives in position over the nail block, at which time the swing plate is at its extreme limit of movement in this direction, and is stopped by contact 110 with a portion of the cross-head.

Pivoted at 156 on the cross head at the opposite side of the nail block from the containers, is nail-transferring or loading mechanism, the oscillating arm 158 of which carries 115 a loader block 160 perforated to receive nails from the usual distributing mechanism (not shown). A spring 162 tends to turn the loader arm toward the right into contact with a stop member 164. The customary loader gate 166 is pivoted at 168 on the under side of the loader arm, serving to sustain the nails in the perforations of the loader block after they have been supplied by the distributing mechanism and until 125 130

they are transferred to the nail block. This gate is latched in its nail-supporting position by the engagement of an opening or depression in it with a projection 170 from the 5 loader arm. When the gate is released from the latch, a spring 172 carries it from beneath the loader block to permit the downward passage of the nails. It may be reset by contact with the stop 164 when the loader 10 arm is moved against said stop by the spring 162. The loader arm is carried into delivery position with its perforations alined with those of the nail block by engagement between a flange 174, shown as depending from 15 the inner edge of the loader arm, and a projection 176 carried by the swing plate. This projection is movable in a socket 178, being held upwardly by a spring 180 seated in the socket beneath the projection. On its side 20 toward the flange 174 the projection is inclined so that, upon contact between the projection and flange in the anti-clockwise or conveying movement of the swing plate, the projection may move across the flange by its 25 depression in the socket. Then, when the swing plate is turned in the opposite direction, the projection carries the loader arm with it, sliding along the inner face of the flange 174, being directed across an opening 30 182 in the flange by a gate 184. This gate is pivoted on the side of the opening toward the axis of rotation of the loader arm and held by a spring 188 in contact with the flange at the outer side of the opening. The 35 swing plate projection 176 rides over the end of this gate, and in so doing the edge of its socket contacts with a lug 190 on the loader gate, disengaging the latter from the projection 170 to deliver the nails. As the 40 projection 176 strikes the flange 174 after slipping from the point of the member 184, it jars the loader block, facilitating the passage of the nails therefrom. This occurs at the end of the clockwise movement of the 45 swing plate and loader arm. Upon anti-clockwise rotation of the swing plate and the travel of the projection in the opposite direction or toward the axis of the loader arm, it contacts with an inclined face 192 50 upon the end of the gate, raising it and allowing the projection to pass through the opening 182. The loader arm is thus released and is turned by its spring against the stop 164, resetting the loader gate. 55 To summarize the operation of the machine, the nailing of a heel and top lift upon a shoe may be considered to have just been completed, the swing plate and loader arm occupying the positions indicated in dotted 60 lines in Fig. 2. At this time, the swing plate projection 176 will have crossed the loader arm flange, in a position to move along its inner side upon the clockwise rotation of the swing plate. The operator now 65 swings out the jack post to remove the shoe

with the attached heel. As an incident to this act, the connecting lever system brings the clutch member into engagement with the bevel gear 46, rotating the swing plate to the left. The projection 176, sliding along the 70 flange, carries the loader arm with it, and, when the loader block reaches the position in which its openings are alined with those of the nail block, the socket of the projection frees the loader gate from its latch 170 by contact with the lug 190, delivering the nails to the block where they are supported upon the drivers. At the same time, the breast gage 84 and the projection 136 have actuated the delivery means of the top lift and heel 75 containers, respectively, to supply these parts to their respective holders, the forks of which are drawn back to receive them. At this time the parts are as illustrated in full lines (Fig. 2). The operator now places the lasted shoe to be heeled upon the jack post spindle and swings it in until the heel seat is above the nail block positioned by the band clamp (not illustrated). In so doing, through the connecting lever system, he 80 shifts the clutch member into engagement with the bevel gear 44, so that the swing plate is rotated in an anti-clockwise direction until stopped by the engagement of the latch 146 with the projection 152. During 85 the first portion of the movement of the swing plate, the projection 176 travels along the loader arm flange toward the gate 184, raising it so that the projection may pass through the opening 182 to free the loader 90 mechanism for its return by its spring to the nail-receiving position. Upon actuating the treadle, the heel nailing operation is performed, and the nailing mechanism in rising trips the latch 146, freeing the 95 swing plate. The friction, which has been slipping during nailing, thereupon carries on the swing plate until the top lift is positioned beneath the heel from which the 100 points of the nails are projecting. The machine is now operated to spank on the top lift and, the parts being in the positions shown in dotted lines in Fig. 2, the operations upon another shoe may be performed. 105 It is to be noted that, after the containers have been supplied with heels and top lifts, the operation of my improved machine is entirely automatic, save for the introduction and removal of the shoes to be heeled, and that, 110 because of the location of the containers at one side of the work and opposite the nail-transferring mechanism, the work-engaging elements are left free for manipulation by the operator, and the conveyance of heel parts and nails is by an organization simply 115 and effectively controlled.

Having described my invention, what I claim as new and desire to secure by Letters Patent of the United States is:

1. In a machine of the class described, a 120

movable work-support, a device movable to bring different work portions into coöperation with each piece of work on the support, movable means for operating upon the work, 5 and means arranged to operate incidentally to different acts performed upon the work for controlling the movements of the device.

2. In a machine of the class described, a movable work-support, a device movable to 10 bring different work portions into coöperation with each piece of work on the support, movable means for performing an operation upon the supported work, and means constructed and arranged to control respectively the movement of the device for 15 such plural work portions through movement of the support and through the movement of the means which performs the operation upon the work.

20 3. In a machine of the class described, a movable work-support, a device movable to bring a work portion into coöperation with the work on the support, power means from which the device may be moved, and means 25 under the influence of the support for controlling the application of power.

4. In a machine of the class described, a movable work-support, a plurality of holding devices movable to bring work portions 30 into coöperation with the work on the support, movable means for operating upon the work, and means constructed and arranged to control such movements for coöperation of different holding devices through the 35 movement of different elements acting upon the work.

5. In a machine of the class described, a movable work-support, a plurality of holding devices movable to bring work portions 40 into coöperation with the work on the support, power means for moving the holding devices, and connections to the work-support for controlling the application of power to the holding devices.

45 6. In a machine of the class described, a movable work-support, a holding device movable to bring work portions into coöperation with the work on the support, power means for moving the holding device in opposite directions, and connections to the 50 work-support for controlling the application of power to the holding device.

55 7. In a machine of the class described, a movable work-support, a plurality of holding devices movable to bring work portions into coöperation with the work on the support, power means for moving the holding devices, connections to the work-support for controlling the application of power to the 60 holding devices, and means independent of the work-support for controlling the holding devices.

8. In a machine of the class described, a movable work-support, a plurality of holding devices movable to bring work por- 65

tions into coöperation with the work on the support, power means for moving the holding devices in one direction to effect successive coöperation between the holding devices and the work, and connections to the 70 work-support for controlling the application of power to the holding devices.

9. In a machine of the class described, a movable work-support, a plurality of holding devices movable to bring work portions 75 into coöperation with the work on the support, power means for moving the holding devices, connections to the work-support for controlling the application of power to move one of the holding devices into coöperation 80 with the work-support, means for retaining the holding device in such position, and means for releasing the retaining means to permit the power means to bring another holding device into coöperation with the 85 work-support.

10. In a heeling machine, a movable jack post, a swing plate coöperating with the jack post, means for moving the swing plate in opposite directions, and connections to 90 the jack post for controlling the moving means.

11. In a heeling machine, a work-support, a heel holder movable into a plurality of positions, a power-shaft, and connections 95 between the power-shaft and holder to effect such movements, the connections being controlled as an incident to acts performed on the work.

12. In a heeling machine, a movable jack 100 post, a swing plate, a power shaft, and means under the control of opposite movements of the jack post for connecting the power shaft and swing plate.

13. In a heeling machine, a movable jack 105 post, nailing mechanism coöperating therewith, heel and top lift holders movable toward the jack post, and means for moving the holders into heel-attaching position under the control of the jack post and in the 110 same direction into top lift attaching position under the control of the nailing mechanism.

14. In a heeling machine, a movable jack 115 post, heel and top lift holders movable into coöperation with the jack post, a power shaft, connections between the power shaft and holders to effect the coöperation of the holders and jack post, and means arranged to control the connections for each movement as an incident to an operation performed upon the work.

15. In a heeling machine, a movable jack 120 post, heel and top lift holders movable into coöperation with the jack post, a power shaft, connections between the power shaft and holders to move the holders to their heel and top lift presenting positions, means controlled by the jack post for determining 125 one of said positions, and means independ. 130

ent of the jack post for determining the other of said positions.

16. In a heeling machine, a movable jack post, heel and top lift holders movable into coöperation with the jack post, a power shaft, connections between the power shaft and holders for moving the holders in one direction to effect their coöperation with the jack post, and means for retaining the holders against movement under the influence of the power shaft at an intermediate point in the travel.

17. In a heeling machine, a movable jack post, heel and top lift holders movable into coöperation with the jack post, a power shaft, connections between the power shaft and holders controlled by the jack post for moving the holders in one direction, means for retaining the holders against movement under the influence of the power shaft, and means for releasing the retaining means for again permitting movement of the holders in the same direction.

18. In a heeling machine, a work-support, oscillatory heel and top lift holders situated initially on the same side of the work-support, and means common to both holders for successively moving them into coöperation with the work-support and for reversing this movement.

19. In a heeling machine, a work-support, a swing plate having heel and top lift holders, means for continuously applying power to the swing plate to move both the holders into coöperation with the work-support, and means for retaining the swing plate against movement during the coöperation of the heel holder and work-support.

20. In a heeling machine, a shoe support, a rotatable spindle, a holder for work portions mounted thereon, power means, and a clutch for connecting the spindle to the power means to bring the work portions into coöperation with a shoe upon the support.

21. In a heeling machine, a rotatable spindle, a holder for work portions mounted thereon, oppositely rotatable power means, and a clutch for connecting the spindle to either power means.

22. In a heeling machine, a rotatable spindle, a holder for work portions mounted thereon, gears rotatable on the spindle, means for oppositely rotating the gears, and a clutch member movable on the spindle into coöperation with the gears.

23. In a heeling machine, a rotatable spindle, a holder for heel parts mounted thereon, two bevel gears rotatable on the spindle, a power shaft having a bevel gear meshing with those on the spindle, and a clutch member mounted on the spindle between the gears for engagement therewith.

24. In a heeling machine, a rotatable spindle, a holder for heel parts mounted thereon, frictional connections between the

holder and spindle, power means, and a clutch for connecting the spindle to the power means.

25. In a heeling machine, a jack post, a rotatable spindle, a heel and top lift holder mounted thereon, power means, a clutch for connecting the spindle to the power means, and connections between the jack post and clutch.

26. In a heeling machine, a jack post, a rotatable spindle, a heel and top lift holder mounted thereon, power means, a clutch for connecting the spindle to the power means, and a lever system connecting the clutch and jack post.

27. In a heeling machine, a rotatable spindle, a swing plate mounted thereon, frictional connections between the swing plate and spindle, power means, a clutch for connecting the spindle to the power means, and a latch device for temporarily retaining the swing plate against movement.

28. In a heeling machine, a rotatable spindle, a swing plate mounted thereon, frictional connections between the swing plate and spindle, power means, a clutch for connecting the spindle to the power means, a latch device for temporarily retaining the swing plate against movement, and means acting in the operation of the machine for releasing the latch device.

29. In a heeling machine, a rotatable spindle, a swing plate mounted thereon, frictional connections between the swing plate and spindle, power means, a clutch for connecting the spindle to the power means, a latch carried by the spindle, and a relatively fixed member with which the latch contacts.

30. In a heeling machine, a jack post, a rotatable spindle, a swing plate mounted thereon, power means, a clutch for connecting the spindle to the power means, connections between the jack post and clutch, and a latch device for temporarily retaining the swing plate against movement.

31. In a heeling machine, work-engaging means, heel and top lift containers situated at the same side of said engaging means, and means for conveying the contents of the containers to the engaging means.

32. In a heeling machine, work-engaging means, heel and top lift containers situated at the same side of said engaging means, means for conveying the contents of the containers to the engaging means, and means for continuously applying power to the conveying means to cause the successive delivery of the heels and top lifts to the engaging means.

33. In a heeling machine, work-engaging means, heel and top lift containers situated at the same side of said engaging means, means for conveying the contents of the containers to the engaging means, means for continuously applying power to the con-

veying means during its operation to cause the successive delivery of the heels and top lifts to the engaging means, and means for retaining the conveying means against movement while the heel is in coöperation with the engaging means.

34. In a heelng machine, work-engaging means, a container for heel parts, means for conveying the heel parts from the container 10 to the work-engaging means and holding them to be acted upon thereby, and means mounted on the container for delivering the heel parts one by one to the conveying means.

15 35. In a heelng machine, work-engaging means, a container for heel parts, means for conveying the heel parts from the container to the work-engaging means and holding them to be acted upon thereby, and means 20 mounted on the container for delivering the heel parts one by one to the conveying means, said conveying means being provided with means for controlling the delivery means.

25 36. In a heelng machine, work-engaging means, a container for heel parts, means for conveying the heel parts from the container to the work-engaging means, and means mounted on the container and acting at its 30 opposite extremities to successively support and release the heel parts therein.

37. In a heelng machine, work-engaging means, heel and top lift containers situated at the same side of said engaging means, 35 holders for conveying the heels and top lifts from the containers to the engaging means, and means mounted on each container for successively supporting and releasing the contents of said container.

40 38. In a heelng machine, work-engaging means, heel and top lift containers situated at the same side of said engaging means, holders for conveying the heels and top lifts from the containers to the engaging means, 45 and means mounted on each container for successively supporting and releasing the contents of said container, the supporting and releasing means for the heel container being outside the line of movement of the holders.

50 39. In a heelng machine, work-engaging means, heel and top lift containers situated at the same side of said engaging means, holders for conveying the heels and top lifts from the containers to the engaging means, 55 and means mounted on each container for successively supporting and releasing the contents of said container, the supporting and releasing means for the heel container being outside the line of movement of the 60 holders and the supporting and releasing means for the top lift container being in the line of movement of the holders and actuated thereby.

65 40. In a machine of the class described, work-engaging means, containers for por-

tions of the work, holders having relatively movable clamping members for conveying the work portions from the containers to the engaging means, means for separating the members of one of the holders for the reception of a part from the corresponding container, and means constructed and arranged to cause the separation of said holding means to separate the members of the associated holder.

70 41. In a heelng machine, heel and top lift containers, heel and top lift holders each having relatively movable clamping members, means for separating the members of one of the holders for the reception of a part from the corresponding container, and a member movable with the clamping member actuated to separate the members of the associated holder.

75 42. In a heelng machine, conveying 80 mechanism for heel parts, means for moving the conveying mechanism, and movable nail-transferring mechanism controlled in its movement by the conveying mechanism.

85 43. In a heelng machine, conveying mechanism for heel parts, means for moving the conveying mechanism, an oscillatory nail-transferring mechanism movable in one direction by the conveying mechanism, and a spring for moving the conveying mechanism 90 in the opposite direction.

95 44. In a heelng machine, conveying mechanism for heel parts, means for moving the conveying mechanism, and a nail-transferring mechanism movable by the conveying mechanism from its nail receiving to its nail-delivering position.

100 45. In a heelng machine, conveying mechanism for heel parts, power mechanism for moving the conveying mechanism, and 105 movable nail-transferring mechanism controlled in its movement by the conveying mechanism.

110 46. In a heelng machine, movable nail-transferring mechanism, and conveying mechanism for heel parts arranged to engage and retain the transferring mechanism in its nail-delivering position.

115 47. In a heelng machine, movable nail-transferring mechanism, and conveying mechanism for heel parts arranged to engage and retain the transferring mechanism in its nail-delivering position, the conveying mechanism during its travel releasing said transferring mechanism.

120 48. In a heelng machine, movable nail-transferring mechanism, conveying mechanism for heel parts arranged to engage and retain the transferring mechanism in its nail-delivering position, and a spring for 125 moving the transferring mechanism to its nail-receiving position.

130 49. In a heelng machine, conveying mechanism for heel parts, and movable nail-transferring mechanism, said mechanisms

being provided with a projection and a wall, one of which is yieldable to enable the normally opposite sides to engage and move in contact to transmit the movement of one mechanism to the other.

50. In a heeling machine, conveying mechanism for heel parts, and movable nail-transferring mechanism, said mechanisms being provided with a projection and a wall, 10 one of which is yieldable to enable the normally opposite sides to engage and move in contact to transmit the movement of one mechanism to the other, the wall having an opening through which the projection may 15 pass to release the mechanisms from one another.

51. In a heeling machine, conveying mechanism for heel parts, movable nail-transferring mechanism, said mechanisms being provided with a projection and a wall movable 20 into engagement with one another in one direction, and means for releasing the engagement on movement in the opposite direction.

52. In a heeling machine, conveying mechanism for heel parts, movable nail-transferring mechanism, one of said mechanisms imparting movement to the other by travel over it in one direction, and means for freeing 25 the mechanisms from one another upon travel in the opposite direction.

53. In a machine of the class described, a plurality of oscillatory carriers, one of said carriers being provided with a longitudinally extending wall having an opening and the other with a projection for engaging and traveling over the wall, and means for permitting the projection to pass 35 through the opening in one direction only 40 of its travel.

54. In a machine of the class described, a plurality of oscillatory carriers, one of said carriers being provided with a longitudinally extending wall having an opening 45 and the other with a projection for engaging and traveling over the wall, and a closure for the opening preventing the passage of the projection in one direction of travel and permitting its passage upon 50 travel in the opposite direction.

55. In a heeling machine, a swing plate provided with a projection, and a loader

arm having a flange engaged by the projection to move the loader arm and retain it in its delivery position.

56. In a heeling machine, a swing plate provided with a projection, and a loader arm having a flange engaged by the projection to move the loader arm and retain it in its delivery position, there being an opening 60 in the flange through which the projection may pass.

57. In a heeling machine, a swing plate provided with a projection, a loader arm having a flange engaged by the projection to move the loader arm and retain it in its delivery position, there being an opening 65 in the flange through which the projection may pass, and a gate coöperating with the flange opening and closing it against passage of 70 the projection upon movement of said projection over the flange in one direction.

58. In a heeling machine, conveying mechanism for heel parts, and movable nail-transferring mechanism provided with a 75 nail-retaining member, the transferring mechanism and retaining member being controlled by the conveying mechanism.

59. In a heeling machine, movable nail-transferring mechanism having a nail-retaining member, and conveying mechanism for heel parts arranged to engage and retain the transferring mechanism in its nail-delivering position and to release the retaining member.

60. In a heeling machine, conveying mechanism for heel parts, and movable nail-transferring mechanism having a movable nail-retaining member, said mechanisms being provided with a projection and a wall, 90 one of which is yieldable to enable the normally opposite sides to engage and move in contact to transmit the movement of one mechanism to the other and to control the nail-retaining member.

61. In a heeling machine, a loader arm having a nail gate latched in its retaining position, and a swing plate provided with a projection for moving the loader arm and releasing the gate.

In testimony whereof I have signed my name to this specification.

BENJAMIN F. MAYO.
